US0D1012491S

(12) United States Design Patent (10) Patent No.: US D1,012,491 S
(45) Date of Patent:  Jan. 30, 2024

(54) BAG

(71) Applicant: Valentino S.p.A., Milan (IT)
(72) Inventor: Pierpaolo Piccioli, Milan (IT)
(73) Assignee: VALENTINO S.p.A., Milan (IT)
() Term: 15 Years
(21) Appl. No.: 35/516,032
(22) Filed: Dec. 19, 2022
(80) Hague Agreement Data

Int. Filing Date: Dec. 19, 2022
Int. Reg. No.: DM/225958
Int. Reg. Date: Dec. 19, 2022
Int. Reg. Pub. Date: Jan. 20, 2023
(51) LOC (14) Cl. 03-01
(52) U.S. Cl.
USPC D3/232; D3/246
(58) Field of Classification Search
USPC D3/232, 234, 238, 242, 243, 244, 245,
D3/246
CPC A45C 3/10; A45C 3/06
